corporation of Massachusetts

Application March 14, 1944, Serial No. 526,413

4 Claims. (Cl. 150—39)

1

This invention relates to an improvement in flexible pocket receptacles designed for carrying pass cards and similar articles either with or without a capacity for carrying other articles such as currency and the like.

One object of the invention is to provide an improved structure which will carry the pass cards with greater security and provide greater convenience in their display.

A further object is to provide a pass card supporting structure which may be permanently or temporarily incorporated with conventional billfold structures with the advantages above mentioned and at the same time obviating certain disadvantages heretofore encountered when pass cards and the like are carried in billfolds.

Other and further objects residing in the details of the construction will be made apparent in the following specification and claims.

In the accompanying drawings which show several illustrative embodiments of the invention,

Fig. 1 is a front elevational view of a pass case embodying my invention, the case being shown open with one of the pass envelopes (shown in dotted lines) swung outwardly of the support to inspection position;

Fig. 2 is a front elevation of the structure shown in Fig. 1, the case being closed;

Fig. 3 is a bottom edge view of the case as shown in Fig. 2;

Fig. 4 is a view similar to Fig. 3 but showing the pass envelopes pivoted at their inner corners;

Fig. 5 is a detail view of one of the pass envelopes, parts being broken away.

Fig. 6 is a front elevational view showing the invention combined with billfold structure, the billfold being shown open and with parts broken away;

Fig. 7 is a sectional view substantially on line 7—7 of Fig. 6;

Fig. 8 is a view similar to Fig. 6 but showing a structure modified to permit removal of the pass carrying unit from the billfold, parts being broken away;

Fig. 9 is an elevational view of the pass carrying unit of Fig. 8 removed from the billfold, parts being broken away;

Figs. 10 and 11 are detail views of the means for releasably holding the pass carrying unit of Figs. 8 and 9 in the billfold, Fig. 11 being a sec-

2

tional view taken substantially on line 11—11 of Fig. 8;

Fig. 12 is a front elevational view showing the manner of assembling and disassembling the pass unit and billfold combination of Fig. 8;

Fig. 13 is a diagrammatic view showing the manner of operation by which the pass envelopes are released from interlocking interference to permit them to be swung outwardly of the billfolds of Figs. 6 and 8;

Figs. 14 and 15 are detail views showing alternative forms of pivotal connections for the envelopes by which the envelopes may be made detachable from the support; and

Fig. 16 is a front elevational view showing another way of combining the pass case of Fig. 1 with billfold structure.

Referring to Figs. 1 to 5 inclusive the pass case is shown as including a supporting member 10, preferably formed of leather or similar flexible material, within the borders of which the pass display envelopes, generally indicated at 11 are normally positioned. The pass envelopes are shown as formed of two pieces of transparent material 12 such as Celluloid or the like held together at one end and both side edges by a suitable binding material as indicated at 13 in Fig. 5. Through the open end 14 of the envelope one or two cards 15, or similar material, may be inserted for display through opposite sides of the envelope. The exact details of the structure of the envelopes as so far described are not important and their construction may be varied as found desirable. According to my invention, I provide the envelopes at one corner with an extending tab 16. This tab may be formed integral with the sheets 12 and is preferably positioned to extend from one side of the envelope adjacent the open end 14. The envelopes are pivotally connected to the supporting member 10 by rivets 17 or similar members passing through openings 18 in the ears. In the drawings, the rivets 17 are shown as passing through both members 10 and 20, but it will be understood that the pivot member may be carried by either one of these elements of the support alone if desired. As shown, in Fig. 1, the envelopes are pivotally connected to member 10 adjacent the outer upper corners thereof so as

to be swung outwardly of the confines of the

member 10 as shown in dotted lines in said figure. The member 10 is formed with a transverse line of fold 19. Preferably one or more envelopes are arranged on opposite sides of the line of fold 19 with their ends 23, which are remote from their pivots, adjacent the line of fold as shown in Fig. 1. End pieces 20 are secured to the ends and bottom edge of the member 10 to form pockets in which the envelopes nest, when within the confines of the member 10, the open ends 14 of the envelopes being positioned adjacent a closed side of the pockets, thus preventing the passes from working outwardly of the envelopes. Members 20 separate and protect the exposed surfaces of the envelopes from rubbing against each other when the support 10 is folded to close the case.

The member 10 is provided with a portion 21 extending from one end thereof. When the case is closed by folding at the line 19 as shown in Fig. 2 the portion 21 may be folded over onto the rear face of the member 10, as shown in Figs. 2 and 3, and secured by a snap fastener 22 to hold the case closed.

The ends 23 of the envelopes remote from their pivots are preferably positioned sufficiently close to the line of fold 19 so that said fold engages or is in near engagement with the ends 23, when the support is folded, to prevent any substantial outward swinging movement of the envelopes. Since the ends 23 thus engaged are the leading ends of the envelopes in their swinging movement their engagement by the fold 19 effectively prevents outward movement of the envelopes while leaving the leading side edges 24 adjacent the pivots free to be grasped when the case is open without any closure flap being in the way. This arrangement also leaves the edges 24 exposed so that they may be provided with index receiving tabs 25, if desired, for facilitating selection of a desired card for inspection.

If, as shown in Fig. 4, the envelopes are pivoted at their corners adjacent fold 19 the envelopes are held within the confines of the case by the engagement with their leading ends of the fold 26 of portion 21.

In Figs. 6 and 7 is illustrated one manner in which the present invention may be advantageously incorporated in a billfold structure. Referring to the latter figures, a billfold is shown comprising an outer wall 30 and inner wall 31 connected together at their end and bottom side edges to form between them an elongated bill compartment 32. A partition wall is shown at 33 which divides the bill compartment in the usual manner. It will be understood that the several wall members may be made up in any conventional or desired manner. As shown (Fig. 7) the partition wall 33 is connected at the bottom to the elements 34 of the inner wall. The billfold walls, as is customary, have a transverse line of fold 35 about which one half of the billfold may be folded on the other. Pass display envelopes 11 which may be identical in form with those previously described are pivotally connected adjacent the outer, upper corners of the partition wall as by rivets 36. In this arrangement the partition wall 33 functions relative to the pass display envelopes for the same purposes and in the same manner as does supporting member 10 in the form previously described, the fold 35 engaging the leading edges of the envelopes when the billfold is closed to prevent outward swinging of the envelopes as does fold 19. Similarly the portions of inner wall member 31 on

opposite sides of the fold line 35 serve in lieu of members 20 of the previously described form.

Numerous pass case and billfold users while desiring on many occasions to carry both their pass cards and currency in one receptacle find it advantageous to have the pass carrying portion of the receptacle separable from the bill carrying portion so that either one may be carried separately. Numerous attempts have been heretofore made to provide a pass case-billfold combination of that character but in most, if not all, of the prior attempts to achieve such combination, separation of the pass case from the billfold either leaves the latter noticeably incomplete and unsightly or the combination is made at the expense of customary and desirable billfold structure, such as auxiliary pocket on the face of the inner walls of the billfold. The desired advantageous separation of the pass case from the billfold may be secured in accordance with the present invention without material alteration in the general appearance of the billfold or impairment of its utility as such.

As illustrated in Figs. 8 to 12 inclusive, I secure the desired separability of the pass case from the billfold by making the supporting element 40 of the pass case in the form of a separable partition in the bill compartment of the billfold, the billfold being generally indicated at 41. When the pass case is in position in the bill compartment of the billfold as in Fig. 8, the combination functions substantially as described in connection with the structure shown in Figs. 6 and 7.

As best shown in Fig. 9, the pass display envelopes 11, identical in form with those previously described, are pivotally connected adjacent the outer, upper corners of supporting member 40 for swinging movement outwardly of the envelopes, whether the support 40 is in partition forming position in the bill compartment as in Fig. 8 or is separated therefrom as in Fig. 9. As shown the end portions 42 of the member 40 are folded inwardly to form pockets in which the open ends of the pass display envelopes seat, the infolded ends 42 and the pockets formed thereby serving the same purposes as members 20, and the pockets which they provide, in the construction of Fig. 1. In order to avoid adding unnecessary bulk to the billfold the members 42 are preferably made relatively narrow. As shown, the end portions 42 are held in position by the rivets 43 which form part of the pivotal connection of the pass envelopes to the support and by additional rivets 44 which pass through spacing blocks 45 below the envelopes. Blocks 45 keep the material of the support from bending sharply against the heads of the rivets 44. The lower edges of portions 42 may of course be stitched or otherwise secured to member 40 to close the lower side of the pockets if desired. The use of spacers such as 45 however is preferable if a substantial number of envelopes is used. Member 40 is provided with a transverse line of fold 46 which functions in the same manner and for the same purposes as fold lines 19 and 35 previously described.

The pass case is preferably releasably held in the bill compartment by providing means at the ends of the mouth of the bill compartment which engage the upper edge of the member 40 outwardly of the center of the pivots 43. As shown this holding means is provided by forming loose L-shaped tongues 47 from the end portions of the turned over portion 48 of the outer wall of

5

the billfold, (see Fig. 10) the remainder of portion 48 being cemented or otherwise fastened down to give the edge of the billfold a finished appearance as is customary. The free ends of the tongues are respectively locked in slits 49 formed in the folded edge of the adjacent front wall members 50 and 51 so that end portions of the upper edges of member 40 are engaged beneath the tongues as shown in Figs. 8 and 11 when the pass case is seated in the billfold. The pass case may be removed from the billfold by crimping the support 40 at the fold line 46, as shown in Fig. 12, to shorten its length sufficiently to disengage one end from beneath the holding tongue.

Preferably in the several forms shown, the leading end edges of the envelopes 11 are not only positioned sufficiently close to the transverse fold line of the support so as to be engaged thereby when the case is closed, but are also sufficiently close to each other so that when the case is unfolded and the envelopes at each side of the fold line lie in the same plane, substantial outward swinging movement of the envelopes is prevented by engagement of the leading end edges of the envelopes on one side of the fold with those on the other side. This arrangement is of particular advantage in the billfold combinations described since the tendency of the envelopes to swing outwardly accidentally is substantially minimized. By flexing the billfold including the envelope supporting member thereof, as diagrammatically indicated in exaggerated form in Fig. 13, so that the planes of the envelopes intersect beyond the borders of the envelopes, the pass display envelopes may be easily moved outwardly of the case. In the form shown in Fig. 1 and in Fig. 16 (later described) the envelopes may be released from interference by flexing the supporting member rearwardly about its transverse line of fold in an obvious manner.

In Fig. 16 pass display envelopes 11 such as previously described are combined with a billfold 53 having conventional auxiliary pockets provided on its inner face between wall members 54 and 55 which are at opposite sides of the transverse fold line 56 of the billfold. The pass display envelopes are normally positioned within the pockets as shown but are pivotally connected to the wall members 55, as at 57, to be swung outwardly of the billfold pockets in substantially the same manner as described with regard to the similar pockets formed by members 20 in Fig. 1. By my invention, the desired pass cards are more available for easy selection and inspection than is the case with previous constructions. As will be apparent, when a selected card is swung to position for inspection, as shown in dotted lines in Fig. 1, the card is automatically inverted so that it is in position to be read by the inspector without turning the pass case around and in most instances without the pass case leaving the hands of the owner. It will also be obvious that the pass case element of the combination shown in Figs. 8 to 12 is incorporated in the billfold without necessitating the omission or modification of any essential or desired auxiliary or other element of the billfold per se. It is also apparent that when the pass case is removed from the combination, the billfold is unchanged in its essential appearance and in its capacity for conventional billfold use.

It is frequently desirable to have the pass display envelopes separable from the pass case. For example, a pass case of large capacity may be

6

kept for storage from which pass containing envelopes may be transferred, as needed, to a case of smaller capacity for carrying. This interchangeability may be obtained by employing a conventional screw post 60, as shown in Fig. 14, for the pivotal connection of the pass envelopes to the support, or by using any other suitable form of releasable connection, such as a hook hasp 61 as shown in Fig. 15.

10. I claim:
1. A pass case including a supporting member having portions foldable one upon the other about a transverse line of fold, pass display envelopes normally positioned within the borders of the supporting member on opposite sides of said line of fold, means connecting the envelopes to the supporting member for pivotal movement in the planes of the envelopes, said means being positioned adjacent a corner of the envelopes and adjacent an edge of the supporting member to permit the envelopes to be swung outwardly of the confines of the supporting member when the latter is unfolded, the leading edges of the envelopes remote from their pivots being adjacent the said line of fold and in engageable proximity thereto when the supporting member is folded, to prevent movement of the envelopes outwardly of the supporting member.
  2. A pass case including a supporting member formed of flexible material and having portions foldable one upon the other about a transverse line of fold, pass display envelopes normally positioned within the borders of the supporting member on opposite sides of said line of fold, means connecting outer corners of opposite envelopes to the supporting member adjacent one edge of the latter for pivotal movement in the planes of the envelopes, the adjacent edges of the envelopes being sufficiently close to said line of fold to be engageable therewith when the supporting member is folded to prevent substantial pivotal movement of the envelopes, and said adjacent edges of the envelopes being positioned in engageable proximity to each other to prevent substantial pivotal movement of the envelopes when the supporting member is unfolded except when the supporting member is flexed to permit the envelopes on opposite sides of said fold line to swing past each other.
  3. A pass case including a supporting member having portions foldable one upon the other about a transverse line of fold, at least two pass display envelopes positioned one at each side of the said line of fold and normally positioned within the border of the supporting member, means connecting a corner of each of said envelopes to said member for pivotal movement in the planes of the envelopes to permit swinging movement of the envelopes outwardly of the confines of the said member, said envelopes being open along one edge for the insertion or withdrawal of pass cards and the like into and from the envelopes, and pockets carried by the supporting member one at each side of the said line of fold in which the envelopes are normally nested with the open side of the envelope adjacent a closed side of the pocket in which it is nested.
  4. A billfold including a plurality of wall forming members providing an elongated bill compartment open along one long side thereof and closed at both ends and the other side, said billfold having a transverse line of fold about which one portion of the billfold may be folded upon the other, a partition forming member within the

bill compartment, at least two pass display envelopes positioned within the bill compartment, one on each side of said line of fold, means pivotally connecting the outer corners of the envelopes, which are adjacent the mouth of the bill compartment, to said partition member for swinging movement outwardly of the bill compartment in the plane of the envelope being swung, when the billfold is unfolded, and means at each end of the bill compartment engaging the edge of the partition member outwardly of the center of said pivotal connections, said last named means forming the only means for retaining the partition member in the bill compartment.
